BOX RATCHET WRENCH

Allen J. Brame, Los Angeles, Calif., assignor to
 Tubing Appliance Company, Inc., Los Angeles,
 Calif., a corporation of California

Application December 18, 1952, Serial No. 326,693

5 Claims. (Cl. 81—61)

1 My invention consists in new and useful improvements in a box ratchet wrench of the type adaptable for use for nut-engaging sockets or having direct nut-engaging members. More particularly the invention relates to wrenches of the general type illustrated and described in the copending application of Herbert L. Fish, Serial No. 234,078 filed June 28, 1951, wherein the wrench head carries a ratchet hub and is provided with an extended shank, adapted to serve both as a handle and as an extension handle mounting means.

In order that a wrench of this type may be of maximum utility, it should be capable of operation from various angles of approach and it should be so constructed as to have adequate strength without bulk, combined with the property of being operable in restricted areas. It should also be so constructed that the stud on a nut being tightened, as it lengthens, does not dislodge the wrench and/or socket from the nut; and in the case of a socket wrench the various sized sockets should be readily interchangeable with a minimum of effort. The wrench of said copending Fish application possesses these advantages, but in its manufacture, its parts are machined from forgings or other similar piece material which requires considerable time, skill and effort in order to produce a completely satisfactory wrench.

It is the primary object of the present invention to provide an improved box ratchet wrench and socket construction which embodies all of the desirable characteristics of the wrench of the said copending Fish application, but is constructed of a series of complementary stampings which are assembled in a manner to provide an extremely high torque value, thus greatly simplifying the construction and assembly of the wrench parts.

Another object of the invention is to provide an improved box ratchet wrench formed of a series of stampings of substantially identical contour and secured together by rivets, the arrangement being such that the rivets themselves carry no sheer loads and are subject to only small tensile stresses necessary to hold the stampings in assembled relationship.

A further object of the invention is to provide a wrench of this character, wherein the wrench head for supporting the ratchet hub, is formed by adjacent ends of a pair of outer metal stampings, spaced to accommodate the peripheral ratchet teeth of the hub, by a series of metal

laminations, the pawl mechanism being supported by the intermediate laminations.

With the above and other objects in view which will appear as the description proceeds, the invention consists in the novel features herein set forth, illustrated in the accompanying drawings and more particularly pointed out in the appended claims.

Referring to the drawings in which numerals 10 of like character designate similar parts throughout the several views;

Fig. 1 is a top plan view of the wrench showing a pivoted extension handle in place;

Fig. 2 is a view in side elevation;

Fig. 3 is a slightly enlarged top plan view with the top stamping broken away; and

Fig. 4 is a longitudinal sectional view taken on line 4—4 of Fig. 3.

In the drawings the wrench body generally indicated by the numeral 5, consists of an annular head 6 adapted to receive a ratchet hub 7, and having an extended shank 8, the latter being provided at its free end with a squared aperture 9 adapted to receive the pivoted squared end 10, of an extension handle 11.

The wrench body 5 consists of a pair of superimposed outer stampings 12 and 13, formed of suitable heat treated metal and spaced by one or more metal laminations 14. The head ends of 30 these stampings are provided with bores 15, which are concentrically aligned when the stampings are assembled, as shown in Fig. 4, to rotatably engage the annular shoulders 16 extending from the top and bottom of the hub 7, as will be hereininafter described.

The spacer laminations 14 are transversely drilled at suitable spaced points 17 and provided with bushings 18 for receiving connecting pins or rivets 19 which pass through and secure the 40 stampings 12 and 13. As shown in Fig. 4, the main web of each stamping is formed with openings to receive the rivets 19 and the defining edges of the openings are dimpled as at 20. The opposed dimples of respective stampings extend 45 inwardly and are received by the corresponding ends of the bushing passageways 17 in the laminations 14, the bushings 18 being of such a length that the opposite end faces of the same are engaged by the inner extremities of respective dimples 20, when the stampings are secured together by the rivets 19.

The plan profile of each of the laminations 14 is identical with that of the extended shank portion 8 of the opposed stampings 12 and 13, but 55 the laminations terminate short of the head por-

tions 6 of said stampings, where their ends assume a concave form as at 21, to accommodate the periphery of an annular series of ratchet teeth 22, extending radially between the opposed shoulders 16 of the hub 7. When the wrench parts are assembled as shown in Fig. 4, the annular series of ratchet teeth 22 lie between the spaced, annular head portions 6 of the stampings 12 and 13, which are of a size and shape to completely overlie the series of ratchet teeth. The oppositely disposed annular shoulders 16 are rotatably supported in the respective bores 15 in the head 6, so as to permit rotation of the hub 7.

The ends of the spacing laminations 14 which jointly form a spacer block, are provided, adjacent the periphery of the series of ratchet teeth 22, with a generally circular recess 23 for receiving a pivotally mounted pawl member 24 and permitting its movement into and out of engagement with the ratchet teeth, under the tension of a suitable spring 25 which urges the free end of the pawl into operative position against the ratchet teeth. This pawl 24 has its pivot point 26 located in the stampings 14, adjacent the recess 23 and is held in place by the opposed inner faces of the outer stampings 12 and 13. Thus, the hub 7 is rotatably supported through its shoulders 16 and the opposed bores 15 in the stampings 12 and 13, while the pawl and spring mechanism for actuating the ratchet, is mounted entirely within the laminations 14, interposed between the stampings 12 and 13.

A central aperture 27 is provided in the hub 7 and is formed with a series of nut-engaging surfaces or teeth which may vary in number depending upon the type of nut to be operated upon or the nature of the fitting with which it is to be used.

It will be readily apparent that the described structure snugly and rigidly confines the ratchet hub 7 for rotation in the hub 6, with a maximum smoothness of operation. The opposed surfaces of the stampings 12 and 13 adjacent the head portion 6, bear respectively on the upper and lower surfaces of the radial projection of the hub, adjacent the series of teeth 22, while the sides of the shoulders 16 bear against the edges of the aligned bores 15 formed in the stampings 12 and 13. A very strong wrench head is thus provided and the top and bottom surfaces of the shoulders 16, being substantially flush with the adjacent surfaces of the head 6, minimum dimensions are maintained without a sacrifice of strength or rigidity.

Furthermore, by providing the stamped and laminated body structure as described, the dimples 20 formed in the stampings 12 and 13, engage the corresponding laminations 14 which carry the pawl 24, and support the loads set up in the use of the wrench, through the webs of the stampings. The hub 7 is supported in all rotative positions through the head extensions 6 on the stampings, while the rivets 19 resist the separating forces in the operation of the wrench.

As before stated, under some conditions the extension 8 may be used as handle itself, particularly when starting the tightening of a nut or the like. The handle extension 11 may then be applied where more force is required.

There are many advantageous features of a wrench constructed in accordance with this invention. For example, its small diameter head and its relatively short length provide a maximum of adaptability for uses in confined places. The ratcheting arc is very small and it has an

extremely high torque value because of the method of manufacture. Furthermore, with this wrench, an operator may use adapters and adjust them to varying lengths by merely pushing them through the central bore in the hub 7.

From the foregoing it is believed that my invention may be readily understood by those skilled in the art, without further description, it being borne in mind that numerous changes may be made in the details disclosed without departing from the spirit of the invention as set forth in the following claims.

I claim:

1. A socket wrench, comprising: a pair of stampings, each stamping including a head portion and an extended shank; a spacer member disposed between said stampings; the shanks of said stampings being formed with coaxially aligned openings registering with passageways transversely extending through said spacer member, the defining edges of the coaxially aligned openings in said shanks being inturned to form integral with said stampings annular shear-resisting elements received within and engaging the wall surfaces at the opposite ends of the passageway registering with the coaxially aligned openings of said stampings; and elongate means extending through said openings and passageway for securing said stampings together with the spacer member therebetween, said elongate means being free of any shear stresses induced into said stampings through reception of said annular shear-resisting elements within the opposite ends of each passageway.

2. A ratchet wrench of the type described, comprising: a pair of stampings, each stamping including a head portion and a shank portion extending therefrom; a spacer member disposed between said stampings, the shank portions of said stampings being formed with coaxially aligned apertures registering with passageways transversely extending through said spacer member, the defining edges of the apertures in said shank portions being inturned to form shear-resisting elements received within and engaging the wall surfaces at the opposite ends of said passageway; elongate means extending through said apertures and passageway for securing said stampings together with the spacer member therebetween; the head portions of said stampings being formed with relatively large coaxially aligned circular openings; a hub member having the opposite ends thereof journaled in said circular openings; a series of ratchet teeth circumferentially formed about said hub intermediate the ends thereof; and at least one pawl pivotally carried by said spacer member and spring biased into engagement with said teeth whereby said hub is rotatably driven as said wrench is rotated.

3. A box ratchet wrench, comprising: a head portion and an extended shank portion, formed of a pair of opposed stampings, and a spacer block interposed between said stampings and of a plan profile substantially similar to the shank portions thereof; the shank portions of said stampings being formed with a plurality of spaced coaxially aligned apertures registering with passageways transversely extending through said spacer block; the defining edges of said apertures being inturned to form shear-resisting elements integral with said shank portions and engaged with the wall surfaces at opposite ends of said registering passageway; said head portion having a bore, a hub journaled for rotation in said

bore, said hub having an opening therein with its wall concentric with the axis of rotation of the hub; nut engaging surfaces formed on the wall of said opening; elongate means extending through said openings and passageways for securing said stampings together with the spacer block therebetween; and ratchet means operatively connecting the hub and spacer block whereby the hub may be rotated upon rotation of the wrench, the forces induced into the hub during use of the wrench being transmitted to said stampings through said shear-resisting elements engaged with the wall surfaces of said passageways.

4. A socket wrench, comprising: a pair of stampings, each stamping including a head portion and a shank portion extending therefrom; a spacer member disposed between said stampings of a plan profile substantially similar to the shank portions of said stampings; the head portions of said stampings being each formed with a relatively large circular opening; a hub member having a radially extending circumferential flange presenting annular oppositely facing shoulders thereon, the opposite ends of said hub member being rotatably mounted in said circular openings; the shank portions of said stampings being formed with coaxially aligned openings registering with passageways transversely extending through said spacer member, the defining edges of the apertures in said shank portions being inturned to form annular shear-resisting elements

to be received within and engaging the wall surfaces at opposite ends of the passageway registering therewith; and elongate means extending through said openings and passageways for securing said stampings together with the spacer member disposed between the shank portions thereof and the hub element between the head portions of said stampings with the inner surfaces of the head portions of said stampings engaged with said oppositely facing shoulders of the hub, said elongate means being free of any shear stresses induced into said stampings through reception of said annular shear-resisting element within the opposite ends of each passageway.

5. A wrench as set forth in claim 4 which includes a series of ratchet teeth arranged about the flange of said hub; and at least one pawl means pivotally mounted on said spacer member and spring biased into engagement with said teeth whereby said hub is rotatably driven as said wrench is rotated.
